UNITED STATES PATENT OFFICE.

EGBERT A. REYNOLDS, OF WEEHAWKEN, NEW JERSEY, ASSIGNOR, BY MESNE ASSIGNMENTS, TO AUDIPHONE COMPANY OF AMERICA, OF NEW YORK, N. Y., A CORPORATION OF DELAWARE.

TRAIN-ANNOUNCING SYSTEM.

Application filed December 17, 1919. Serial No. 345,663.

To all whom it may concern:

Be it known that I, EGBERT A. REYNOLDS, a citizen of the United States of America, residing at Weehawken, county of Hudson, 5 State of New Jersey, have invented certain new and useful Improvements in Train-Announcing Systems, of which the following is a specification.

This invention relates to train announcing systems and is particularly applicable for street and railroad trains.

An object of this invention is to provide an improved simple and effective means of announcing stations and the transmission 15 of other intelligence to different parts of a train of cars or other vehicles, simultaneously from a single announcing unit. A further object of the invention is to provide an electrical system for electrical transmission and an announcing unit constructed 20 and arranged to be automatically connected in or disconnected from the system, whereby the continuity of the train circuit is preserved when the unit is disconnected from 25 any particular car and the proper connections effected when the unit is inserted at any location of the system.

The most preferred forms of my invention comprise a wiring circuit and local battery or other electrical source for each car 30 or other unit, such wiring circuit being preferably uniform for the several car units, and one or more terminal blocks adapted to be positioned at either the front, rear or 35 intermediate door or doors, the wiring circuits of the respective cars being provided with suitable openings for connecting the cars electrically together and an announcing unit provided with a sound receiving 40 element. The sound emitting element comprises preferably a split horn or trumpet located in the center of the car, the two discharge openings of such split horn being directed to effectively emit the sounds 45 clearly to all parts of the car.

A suitable announcing device or other sound receiving element is provided with contacts, such announcing device and its contacts being mounted on a unitary base, the 50 contacts projecting from the rear face of the base for connecting in the local battery and providing proper connection with the wiring circuit, whereby upon insertion of the resulting announcing unit in the ter-

minal block of any car, the connection is at 55 once effected with the sound emitting elements of the train system. The contacts of the announcing unit and the corresponding contact socket openings of the terminal block are arranged in a predetermined 60 spacing to insure proper position of the announcing unit in the terminal block. Upon withdrawal of the announcing unit from the terminal block, the circuit of such car is restored for operation of the system upon 65 insertion of the announcing unit in any other terminal block of the train.

Further features and objects of the invention will be more fully understood from the following description and the accompanying drawings, in which

Fig. 1 is a diagrammatic plan view of a train comprising five cars and equipped with my invention;

Fig. 2 is a front face elevation of a terminal block of my system shown somewhat enlarged;

Fig. 3 is a rear face elevation of Fig. 2;

Fig. 4 is a detail, perspective view of a preferred form of contact of my terminal 80 block;

Fig. 5 is a front face elevation of one form of announcing unit of my system;

Fig. 6 is a rear perspective view of Fig. 5; and

Fig. 7 is a diagrammatic view of the electrical connections.

Referring to Fig. 1, the cars or other vehicles of the train are indicated at 1, 2, 3, 4 and 5. In each car is suitably positioned 90 a split horn or trumpet 6 having divergent discharge openings directed toward the opposite ends of each car. The receiver of such horn 6 is preferably of such construction described and claimed in the pending 95 application of De Elbert Reynolds, and Egbert A. Reynolds, Serial No. 183,215 filed July 28, 1917, or of any suitable, approved electrical type, as will be understood by the art, and is indicated at 7 in the enlarged view in Fig. 7. The announcing unit or other sound receiving unit indicated at 8, see Figs. 5 and 7, is of any approved type and is preferably associated with the amplifying coil 9, see Figs. 5 and 7, as described more fully hereinafter. The leads from the announcing unit 8 to the primary 100 of the induction coil 9 are indicated at 105

11, 12, one of which is provided with a suitable cut out switch 13, as indicated in Figs. 5 and 7. The primary wiring 10 in Figs. 5 and 7 is shown extending over two sections of the amplifying coil 9, whereas the secondary of the amplifying coil 9 is formed of two separate windings 14, 15. The lead 16 from one terminal of one secondary 14 connects with the contact 17 and the lead 18 from the other terminal of the secondary connects with the contact 19. Similarly, the lead 20 from one terminal of the other secondary 15 of the amplifying coil 9 is connected with the contact 21 and the lead 22 connects the other terminal of the secondary 15 with the contact 23. The announcing unit 8 and the primary 10 of the induction coil 9 are provided with the contacts 24, 25, for connection with the battery 26 of the particular car.

Preferably such transmitter 8 and amplifying coil 9 and the contacts are mounted on the unitary block 26 of insulating material, such contacts 17, 19, 21, 23, 24 and 25 project through and beyond the rear face 27 of the block 26.

It will be noted that the contacts 17, 19, 21, 23, 24, and 25 are spaced apart from one another in a predetermined relation for the purpose of ensuring proper insertion of the contacts and therewith of the announcing unit and amplifying coil 9, or the announcing unit as a whole into the terminal block of the system to properly connect the same in the train system in proper circuit relation.

The terminal block comprises the base 30 on which are mounted contact sockets on the rear face 31 of the terminal block 30 and openings projecting through the block 30 from the rear face to the front face 32. The respective openings of the contact terminals of the terminal block are arranged in spacial relationship to one another corresponding to the predetermined spacial relationship of the aforesaid contacts of the announcing unit, as will appear by comparison of Figs. 2 and 6. Specifically the contact socket 33 is connected by the lead 34 to one terminal of the battery whereas the contact socket 35 is connected by the lead 36 to the opposite terminal of the battery 26. The contact openings of the contact sockets 33, 35 are respectively designated 37', 38', as shown in Fig. 2.

The contacts for the respective secondaries are of dual contact form and arranged upon insertion of an announcing unit to connect the terminals 17, 19, and 21, 23, with the respective pairs of lead wires running to the forwardly disposed horns 7, and the rearwardly disposed horns 7, and upon withdrawal of the announcing unit from the particular terminal block, connection is automatically established between

the respective contact portions of the dual contacts to properly connect the lead wires of the particular car into the circuit system of the train. Upon withdrawal of the announcing unit from the terminal block of 70 a particular car, the battery 26 of such particular car is open-circuited.

In the specific terminal block shown in the drawings of the application, the contact 17 of the secondary winding 14 of the amplifying coil 9 coacts with the set of contact strips 37, 38, whereby upon insertion of the contact 17 through the socket opening 39 passing through the block 30, the contact strip 37 is moved out of operative 75 position relative to the contact strip 38, as is indicated diagrammatically in detail on an enlarged scale in Fig. 4. Upon withdrawal of the contact 17 from the socket opening 39, the contact strip 37 springs 80 back and restores its electrical connection with the contact strip 38, i. e., through the button 39' of contact 38. The contact strips 37, 38 are mounted at their non-contacting 85 ends in the insulation block 29.

Similarly, the contact 19 of the secondary winding 14 of the amplifying coil 9 coacts with the set of contact strips 40, 41, the latter being provided with the contact button 42, whereby upon insertion of the contact 19 through the socket opening 43 in the base 30, the contact 40 is moved out of contact with the contact 41 and upon withdrawal of the contact 19 through the socket opening 14, the electrical connection between contacts 40 and 41 is restored.

Also, in a similar manner, the contact 21 of one end of the secondary winding 15 of the amplifying coil 9 cooperates with the set of contact strips 44, 45, the latter having 105 the contact button 46, and the socket opening 47 in the block 30 is provided for reception of the contact 21.

And similarly, the other contact 23 of the secondary winding 15 of the amplifying coil cooperates with the set of contact strips 48, 49, the latter being provided with the contact button 50 and the socket opening 51 provided in the block 30 for insertion of the contact 23.

Fig. 4 illustrates as well the operation of the respective sets of contact strips 40, 41 and 44, 45, and 38, 39, as the set of contacts 33, 35, as described in particular hereinabove.

The contact 37 is connected by the lead 52 to one terminal of a horn 7 and the contact 40 connected by the lead 53 with the other terminal of the same horn 7. Taking car No. 3, for example, as indicated in Fig. 1, in which figure the announcing unit indicated at 54 is shown inserted in the terminal block adjacent the forward door, indicated at 55, of car 3, such wires 52, 53, extend to the right and connect with the ter-

minals of the horn 7 disposed at substantially the center of the car 3.

Similarly, the contact strip 44 is connected by the lead 56 and the contact strip 48 by the lead 57, see Figs. 1 and 3, with the circuit leading to one or more horns 7 disposed to the left of the aforesaid position 54 of the announcing unit in car 3, as shown in Fig. 1.

10 The contact strip 38, see Fig. 3, is connected by the lead 60 with the contact strip 45, and the contact strip 49 by the lead 61 with the contact strip 41.

Specifically, said leads 56, 57, see Fig. 1, 15 run to the terminal block indicated at 58 positioned, say, adjacent the rearward door of the car 2 and by reason of the absence of any announcing unit inserted in such terminal block 58, similar to the aforesaid terminal block shown in Fig. 3, connection is 20 made through the corresponding sets of contact strips with the leads running to the terminals of the horn 7 in car 2, and similarly through the terminal block at the forward 25 door of car 2, thence through the wiring circuit through the terminal block at the rearward door of car 1, and thus to the terminals of the horn 7 in car 1.

Similarly, the horns 7 of cars 4 and 5 are 30 connected in tandem in the wiring circuit through the respective terminal blocks shown as disposed adjacent the rear door of car 3, the forward and rear doors of car 4 and the forward and rear doors of car 5, etc. It will be noted that the battery 26 of car 3 is in circuit through the contacts 33, 35 of the terminal block adjacent the front door of car 3, said terminals 33, 35 coacting with the terminals 24, 25 of the announcing 35 unit 54, whereas the batteries of the other cars are thrown out of circuit.

The connection from car to car of the two wire circuits is made by means of any suitable circuit coupling as will be understood 40 by the art.

Upon withdrawal of the announcing unit 54 from the particular position shown in Fig. 1, namely from the terminal block 58, and the insertion of the announcing unit 54 in any other terminal block of the train, the wiring circuit of the horns is established through the terminal block 58 adjacent the front door 55 of car 3 preparatory for insertion of the announcing unit in any other 55 terminal block of the train circuit.

In a similar manner the invention is applicable for use in communication systems in factories and other buildings for the exchange of communication from any variable location of announcing to one or more locations of reception. For purposes of simplification, I have shown my invention applicable to a two wire circuit system and embodying amplifying means formed of two 60 secondaries, the respective secondaries con-

trolling sound emitting devices located forwardly and rearwardly of the location of announcing, but such specific circuit arrangement may be varied to embody any approved communicating system or particular communicating devices as may be desired. It will particularly be observed that the induction coil need not be formed of an integral core common to both or all secondaries and that I may employ two or more 70 separate amplifying coils, each amplifying coil embodying a single primary and a single secondary arranged to carry out the aforesaid objects of the invention.

It will also be noted that the contacts of 80 the announcing unit may be arranged in a different order or different special relationship from that shown in Fig. 6, to provide the predetermined spacial relationship between such contacts to ensure proper positioning of the announcing unit in any terminal block of the system.

Whereas I have described my invention by reference to specific forms thereof, it will 85 be understood that many changes and modifications may be made without departing from the spirit of the invention, as defined by the appended claims.

I claim.

1. In a train of separable vehicles, a sound 90 emitting device for each of said vehicles, lead wires carried by each vehicle connected to the terminals of said sound emitting device, a source of electrical energy carried by each vehicle, contacts for said lead wires and said source, insulating means in each vehicle for unitarily mounting said contacts in adjacent relation, a sound receiving device, an amplifying coil, contacts for said 95 amplifying coil separable from said first-named contacts and unitary means for mounting said sound receiving device and said amplifying coil and said separable contacts for said amplifying coil.

2. The combination of a plurality of 100 sound emitting devices, lead wires connected to the terminals of said sound emitting devices respectively, a source of electrical energy, contacts for said lead wires and said source, insulating means for unitarily 105 mounting said contacts in adjacent relation, a sound receiving device, an amplifying coil comprising primary and secondary windings, lead wires connecting said sound receiving device with the terminals of said 110 primary windings, contacts for the secondary windings separable from said first-named contacts and unitary means for mounting said sound receiving device and said amplifying coil and said separable contacts.

3. In a communicating system, a plurality 115 of sound emitting members disposed at spacially related locations, a pair of leads for each of said members, sets of separate con- 120

4

tacts connected to said pairs of leads respectively, means disposed correspondingly to said spacially related locations for mounting in common the corresponding contacts 5 of said sets of contacts, sources of electrical energy disposed correspondingly to said spacially related locations, said sources of electrical energy being normally disconnected from said pairs of leads, a sound 10 receiving member, contacts for said sound receiving member, an amplifying device and a device for mounting in common said sound receiving member, said sound receiving member contacts and said amplifying 15 device, said common mounting device being constructed to be removably assembled at will with any particular one of said spacially related common mounting means, said sound receiving member contacts being 20 mounted on said device to effect connection with the source of electrical energy corresponding to the particular spacially related common mounting means while disconnecting the remainder of said sources of electrical 25 energy.

4. In a communication system, a sound receiving device, a plurality of sound emitting devices, a pair of leads respectively connected to each of said sound emitting 30 devices, a pair of contacts for each of said leads, means for mounting said pairs of contacts in adjacent relation, said contacts of each pair being normally in electrical contact with one another, contacts for said 35 sound receiving device, means for unitarily mounting said last-named contacts and said sound receiving device and means for supporting said unitary mounting means on said first-named mounting means and for 40 moving the contacts of each of said pairs of contacts out of electrical contact with one another.

5. In a communication system, a sound receiving device, a plurality of sound emitting devices, a pair of leads respectively connected to each of said sound emitting devices, a pair of contacts for each of said leads, means for mounting said pairs of contacts adjacent one another and in a pre- 45 determined relation to one another, said contacts of each pair being normally in electrical contact with one another, contacts for said sound receiving device, means for unitarily mounting said last-named contacts, 50 and said sound receiving device, and means for supporting said unitary mounting means on said first-named mounting means and for moving the contacts of each of said pairs of contacts out of electrical contact with one another.

6. In a communication system, a sound receiving device, a plurality of sound emitting devices, a pair of leads respectively connected to each of said sound emitting 55 devices, a pair of contacts for each of said

leads, common means for mounting said pairs of contacts in adjacent relation, said contacts of each pair being normally in electrical contact with one another, contacts for said sound receiving device, means for unitarily mounting said last-named contacts and said sound receiving device, and means supporting said unitary mounting means on said first-named mounting means and for moving the contacts of each of said pairs 70 of contacts out of contact with one another. 75

7. In a communication system, a sound receiving device, a plurality of sound emitting devices, an amplifying device, a pair of leads respectively connected to each of said sound emitting devices, a pair of contacts for each of said leads, common means for mounting said pairs of contacts in adjacent relation, said contacts of each pair being normally in electrical contact with 80 one another, contacts for said sound receiving device, means for unitarily mounting said last-named contacts, said amplifying device and said sound receiving device, and means supporting said unitary mounting 85 means on said first-named mounting means and for moving the contacts of each of said pairs of contacts out of electrical contact with one another.

8. In a communication system, a sound receiving device, a plurality of sound emitting devices, a pair of leads respectively connected to each of said sound emitting devices, a pair of contacts for each of said leads, common means for mounting said pairs of contacts in predetermined adjacent relation, said contacts of each pair being normally in electrical contact with one another, contacts for said sound receiving device, means for unitarily mounting said last-named contacts in a corresponding predetermined relation, and means supporting said unitary mounting means on said first-named mounting means and for moving the contacts on each of said pairs of contacts 100 out of electrical contact with one another.

9. In a communication system, a sound receiving device, a plurality of sound emitting devices, an amplifying device, a pair of leads respectively connected to each of said sound emitting devices, a pair of contacts for each of said leads, common means for mounting said pairs of contacts in predetermined adjacent relation, said contacts of each pair being normally in electrical contact with one another, contacts for said sound receiving device, means for unitarily mounting said last-named contacts in a corresponding predetermined relation, together with said amplifying device and said sound receiving device, and means supporting said unitary mounting means on said first-named mounting means and for moving the contacts of each of said pairs of contacts out of electrical contact with one another.

10. In a communicating system, a plurality of sound emitting members disposed at spacially related locations, a pair of leads for each of said members, sets of separate contacts connected to said pairs of leads respectively, means disposed corresponding to said spacially related locations for mounting in common the corresponding contacts of said sets of contacts, said common mounting means being each provided with openings located at predetermined spacings, sources of electrical energy disposed correspondingly to said spacially related locations, said sources of electrical energy being normally disconnected from said pairs of leads, a sound receiving member, an amplifying device, contacts for said sound receiv-
- ing member and said amplifying device located to one another corresponding to said predetermined spacings, and a device for 20 mounting in common said sound receiving member, said amplifying device and said sound receiving member and amplifying device contacts, said sound receiving member and amplifying device contacts projecting 25 from said common mounting device to be received within said openings of said common mounting means respectively to thereby connect in the source of electrical energy corresponding to any particular one of said 30 mounting means.

In testimony whereof I have signed this specification this 3rd day of December, 1919.

EGBERT A. REYNOLDS.
